UNITED STATES PATENT OFFICE.

KURT E. RICHTER, OF NEW YORK, N. Y.

TOBACCO-BOX.

1,166,079.

Specification of Letters Patent. Patented Dec. 28, 1915.

Application filed November 24, 1913. Serial No. 802,818.

To all whom it may concern:

Be it known that I, KURT E. RICHTER, a citizen of the United States, residing at New York, in the county of New York, in the State of New York, have invented a new and convenient Tobacco-Box.

The invention relates to boxes or containers for tobacco, and has for an object to provide a box particularly adapted to contain cigarettes and which has a suitable igniting element arranged for convenient use to light one of the cigarettes, the igniting element, however, being separately retained and arranged in the box so as to prevent them from coming in contact when the box is in the pocket and prevent the igniting element from injuring the cigarettes or vice versa; the igniting element furthermore being so arranged that the box can be safely carried in the pocket without danger of accidental ignition of the element.

In the further disclosure of the invention reference is to be had to the accompanying drawings, constituting a part of this specification, in which similar characters of reference denote corresponding parts in all the views, and in which:

Figure 1 is a perspective view of the box, showing the same partially open; Fig. 2 is a perspective view of the body of the box, with the cover for the igniting element shown in open position; and Fig. 3 is a vertical transverse sectional view taken through the box when the same is within its closure.

Referring more particularly to the views, I disclose a box 10 and a closure 11 therefore, the same being in the nature of a carton, with the box formed to provide a back wall 12, end walls 13, a lid 14 and a front wall 15 which is formed with the body of the box at its lower end and, therefore, is free to swing. The closure 11 is formed in a substantially rectangular shape and the box is adapted to slide within the closure, as will be readily seen by referring to the views, the lid 14 when bent over upon the front wall 15 being adapted to be held closed by the closure 11 when the box is arranged within the closure, as will be readily seen by referring to Fig. 3.

Secured to the face of the front wall 15 in any suitable manner, but preferably by a staple 16, are a series of igniting elements 17 in the nature of safety matches or the like and secured at its lower end to the front

wall 15 beneath the point of attachment of the elements 17 is a cover 18 for the igniting elements and which is preferably formed of a single piece of stiff cardboard or paper, said cover, by reason of its connection with the front wall, being adapted to swing or hinge thereon and having on its inner face an igniting surface or plate 19 upon which one of the igniting elements 17 is adapted to be rubbed for the purpose of igniting the same.

Now referring to Fig. 3, it will be clearly seen that when the box lies within the closure the cover 18 will be held in covering position so that the igniting elements will lie between the front wall of the box and the closure, said front wall spacing the igniting elements from the cigarettes adapted to be contained in the compartment 20 of the box. When the box is partially removed from the closure it will be seen that the covering can be bent or swung downwardly so as to expose the igniting elements and permit of the removal of one of them and the subsequent rubbing thereof upon the igniting plate and which will also be exposed by the downward swinging movement of the cover, as shown in Fig. 2. When the box is returned within the closure the association of the box with the closure will cause the closure to act upon the cover 18 and swing the same into position against the igniting elements so as to cover the same and protect the igniting elements.

From the foregoing description it will be clearly seen that the structure described provides a neat and compact package in which cigarettes and igniting elements can be conveniently carried in a unitary and compact manner without danger of the cigarettes being injured by the igniting elements or the igniting elements being injured by the cigarettes when the box is carried in the pocket, the igniting elements, furthermore, being protected against accidental ignition, particularly in case they are not of the safety variety.

I claim—

The combination with a cigarette box embodying an open ended casing substantially rectangular in cross section, and a cigarette container slidably mounted within said casing and comprising a back wall, end walls, a bottom wall, a front wall having the lower end formed integral with the forward end of said bottom wall and the side

edges free of the forward edges of said end walls, and a top wall having the rear edge secured to the upper edge of said back wall and the forward end formed to provide a flap adapted to be inserted between the front walls of said container and casing to close the upper end of the container, of a plurality of striking elements secured to the outer surface of the front wall of said container, a flap having the lower portion secured to the outer surface of the front wall of the container below said striking ele-

ments and adapted to overlie the striking elements to protect the same from the front wall of said casing in the sliding of said container, and an abrading element secured to the inner surface of said flap adjacent to the lower end thereof upon which said striking elements may be ignited. 15

KURT E. RICHTER.
